DESIGN FOR A HANDLE FOR TRAY OR THE LIKE

Frank Abelson, New York, N. Y.

Application January 8, 1946, Serial No. 125,344

Term of patent 3½ years

(Cl. D44—10)

To all whom it may concern:

Be it known that I, Frank Abelson, a citizen of the United States and residing at New York, in the county of New York and State of New York, have invented a new, original, and ornamental Design for a Handle for Tray or the Like, of which the following is a specification, reference being had to the accompanying drawing, forming part thereof, and in which

Fig. 1 is a plan view of a handle for a tray or the like, showing my new design,

Fig. 2 is a side elevational view thereof, and
Fig. 3 is an end elevational view thereof.

I claim:

The ornamental design for a handle for tray or the like, substantially as shown.

FRANK ABELSON.
